UNITED STATES PATENT OFFICE.

HARRY M. KORETZKY, OF NEW YORK, N. Y.

DESIGN FOR A POCKET FLASH-LIGHT.

47,870.

Specification for Design. Patented Sept. 21, 1915.

Application filed January 29, 1915. Serial No. 5,150. Term of patent 14 years.

To all whom it may concern:

Be it known that I, HARRY M. KORETZKY, a subject of the Czar of Russia, and a resident of the city of New York, borough of the Bronx, in the county of the Bronx and State of New York, have invented a new, original, and ornamental Design for a Pocket Flash-Light, of which the following is a specification, reference being had to the accompanying drawing, forming part thereof.

The figure is a perspective view of the pocket flash light.

I claim:

The ornamental design for a pocket flash light, as shown.

HARRY M. KORETZKY.
